UNITED STATES PATENT OFFICE.

HENRY C. FLETCHER, OF NEW CASTLE, PENNSYLVANIA.

COLLAR.

1,079,696.

Specification of Letters Patent.

Patented Nov. 25, 1913.

Application filed August 13, 1912. Serial No. 714,929.

To all whom it may concern:

Be it known that I, HENRY C. FLETCHER, a citizen of the United States, residing at New Castle, in the county of Lawrence and 5 State of Pennsylvania, have invented a new and useful Collar, of which the following is a specification.

This invention relates to shirt collars, and particularly to that class known as double 10 standing, lay-down or turn-down collars wherein the ends of the face are designed to fit close together.

It is the object of the present invention to provide such a collar wherein the ends 15 may be readily engaged to the front collar button, the collar button hole in the end of the collar last engaged being so designed that its engagement to the collar button may be expedited or rendered easy and convenient.

With the foregoing general object in view, the present invention resides in providing that end of the collar which is last attached with the novel form of collar button opening 20 as hereinafter set forth in detail.

The invention has been illustrated in its preferred embodiment in the accompanying drawings, wherein like reference characters have been employed to denote corresponding 30 parts, and wherein—

Figure 1 is a perspective view of the collar when closed, or as when engaged to the front collar button. Fig. 2 is a fragmental perspective of the ends of the collar showing 35 the free end of the collar being engaged to the collar button. Fig. 3 is a view similar to Fig. 2, the free end of the collar being engaged to the collar button at a different position. Fig. 4 is an interior elevation of 40 the ends of the collar. Fig. 5 is a view similar to Fig. 4 showing a slight modification in the form of the button holes or openings.

Referring specifically to the drawings, the collar which is of a double standing, turn-down or lay-down type comprises the usual band 7 and the face 8, the ends of the band projecting beyond the ends of the face and being designed to overlap, as is customary. This collar may be of linen or similar material, and it is also understood that this 50 invention is equally applicable to celluloid or rubber collars or collars of any other material.

In carrying out the present invention, the 55 end of the band which is first engaged to the front collar button is provided adjacent

its lower edge with the usual slit opening for the reception of the collar button in case of a linen or similar collar, or with the usual key-hole collar button opening 9 in case of a rubber collar or the like, the head 10 of which is arranged directly in rear of the end of the face and the tail 11 of which projects outwardly. The head 10 of the key-hole opening is of sufficient diameter to readily 60 receive the head of the collar button as is desirable and customary in rubber collars, and the tail 11 is comparatively short and narrow to provide a notch for accommodating the shank of the collar button, the corresponding end of the collar being engaged to the collar button by passing the head of the key-hole opening over the head of the collar button and then permitting the shank of the collar button to slide into the tail or 65 notch 11.

The most important feature of the present invention resides in the provision of the novel form of collar button opening in the end of the collar last attached to the collar 70 button, this opening being designated by the numeral 12 and being enlarged or preferably vertically elongated directly in rear of the end of the face, or being of a rectangular or other contour arranged in a vertical or other 75 position. The lower end of the opening 12 terminates at a distance from the lower edge of the band corresponding with the distance of the tail 11 of the key-hole opening from the lower edge of the band, the opening 12 80 having a tail 13 projecting outwardly from its lower end in order to provide a notch complementing the tail or notch 11. This notch 13 is on a line with the lower end of the opening 12 and projects laterally relative to the said opening, the opening 12 85 extending upwardly for a considerable distance. The outer edge of the opening 12 90 having a tail 13 projecting outwardly from its lower end in order to provide a notch complementing the tail or notch 11. This notch 13 is on a line with the lower end of the opening 12 and projects laterally relative to the said opening, the opening 12 95 extending upwardly for a considerable distance. The outer edge of the opening 12 100 is substantially vertical and extends from a point adjacent the lower edge of the band to a point short of the upper edge of the band and along the end of the face. It may be stated that the collar button notch 13 which complements the collar button opening in the other end of the collar terminates at its inner end in an enlarged or elongated (vertically or otherwise) opening directly in rear of the corresponding end of the face.

The collar button openings may be readily 110 provided in the band and do not materially weaken the collar, but on the other hand

- provide convenient means for attaching the ends of the collar to the front collar button.
- After the one end of the collar has been engaged to the front collar button, namely, 5 by engaging the key-hole opening or slit over the head of the collar button so that the shank engages in the tail of the key-hole opening, the free or last engaged end of the collar is passed under the opposite 10 end of the face and over the other end of the band and is drawn around to a suitable position, in order that the head of the collar button passes through the opening 12. When this has been done, the free end of the 15 collar is slid, the outer edge of the opening 12 sliding along the shank of the collar button, so that when the end of the collar has been slid upwardly to its proper position, the shank of the collar button will be drawn 20 into the tail or notch 13 of the opening 12. The free end of the collar is thus readily attached to the collar button in a convenient and simple manner, permitting the ends of the face to fit close together and the button hole opening being hidden from view.
- 25 It will also be apparent that the collar button will lie centrally between the ends of the face, so that this invention may be employed with made-up ties or with the customary four-in-hand or bow ties with equal effect. It will also be observed that the enlarged or elongated opening 12 permits the said opening to be readily passed over the head of the collar button regardless of the 30 particular position of the free end of the collar, and that by drawing the free end of the collar upwardly, the shank of the collar button will be drawn into the notch 13. It is also unnecessary to spring the ends 35 of the face or the ends of the band, as is customary with the collars known to the trade as "Ara-notch" collars, or collars which are provided at their free or last engaged ends with an opening extending to 40 the lower edge so that the free end of the collar may be slipped downwardly over the collar button and the free end of the band may then be snapped under the opposite end of the face.
- 45 50 A collar provided with collar button openings in accordance with the present invention may be most readily engaged to the front collar button, even in the dark, and the appearance, convenience or use of the collar is not in any manner interfered with,

but on the other hand, are increased in efficiency.

In the form illustrated in Fig. 5, the collar button opening 9' in the end of the collar which is first attached is provided with a head 60 10' and oppositely projecting tails or notches 11' as is common in rubber or like collars, so that it will appear that the collar button opening may be of any preferred form. The collar button opening in the free end 65 or last engaged end of the collar is modified, in that the lower end of the opening 12' terminates a considerable distance above the lower edge of the band and the tail 13' projects diagonally downward and outward to 70 the proper position to complement an opening in the other end of the collar. This last mentioned form may be employed with the same convenience and efficiency as the form above described, as will be apparent. 75 It will therefore be understood, that the collar button openings may be slightly modified in form and position to be in accord with the dictates of convenience or efficiency. This invention is also applicable with equal 80 propriety to various forms or styles of collars as are common under the class of double standing, turn-down or lay-down collars.

Having thus described the invention what is claimed as new is:

A lay-down collar wherein the ends of the face are designed to fit close together and wherein the ends of the band are designed to overlap, the band being provided at its last attached end with an enlarged 90 collar button opening directly in rear of the corresponding end of the face to readily receive the head of the collar button and having an outwardly projecting notch at its lower end extending toward the end of the band to receive the shank of the collar button, the outer edge of the opening being substantially vertical and extending from a point adjacent the lower edge of the band, along the end of the face and to a point 95 short of the upper edge of the band, so that the said outer edge of the opening may slide on the shank of the collar button.

In testimony that I claim the foregoing as my own, I have hereto affixed my signature in the presence of two witnesses.

HENRY C. FLETCHER.
